UNITED STATES PATENT OFFICE.

ROBERT A. SALLEE, OF MIDDLETOWN, CALIFORNIA.

COMBINATION SUCTION ELEVATOR AND LOADER.

1,100,992.

Specification of Letters Patent. Patented June 23, 1914.

Application filed March 18, 1913. Serial No. 753,978.

To all whom it may concern:

Be it known that I, ROBERT A. SALLEE, a citizen of the United States, residing at Middletown, in the county of Lake and State of California, have invented new and useful Improvements in Combination Suction Elevators and Loaders, of which the following is a specification.

This invention relates to a combined suction elevator and loader which is particularly adapted for elevating granular materials, such as sand, gravel, and the like.

The object of the invention is to produce a suction elevator and loader, which is simple, inexpensive, and substantial in construction, and which is provided with means for automatically and continuously discharging material delivered to the receiving chamber of the apparatus.

Another object is to provide a secondary pressure chamber from where the material may be further elevated or conveyed by pressure to the point of discharge.

The invention consists of the parts and the construction and combination of parts as hereinafter more fully described and claimed, having reference to the accompanying drawings, in which—

Figure 1 is a central vertical section of the device. Fig. 2 is a plan view of the apparatus.

This invention relates to a suction elevator and loader which has proven particularly adaptable for elevating such materials as sand, gravel, and the like.

The apparatus consists of a cylinder or container A, the upper portion of which is connected by a pipe 2 with a suitable vacuum pump, not here shown. The upper portion 40 of the cylinder connected with the vacuum source is separated from the lower portion of the cylinder, which is large enough to form a temporary container for the elevated material, by a perforated plate or screen 3; 45 the object of this screen 3 being to prevent any of the material entering through the elevating pipe 4 from escaping through the suction pipe. The bottom of the elevator is provided with a discharge opening 5, 50 which opens directly into an inclined discharge cylinder 6, suitably supported within a casing B with relation to the temporary receiver. Suitably secured to an endless cable, passing over a driving pulley 7 and an 55 idler 8 suitably journaled in the casing B, are a series of piston members 9 which enter the

cylinder in regular order, as shown, the spacing of the pistons being such that the ends of the cylinder will be closed at all times, thus preventing admission of air to the 60 vacuum chamber. For the purpose of discharging the air entering the upper end of the discharge cylinder 6, previous to the admission of each individual piston member, it is desirable to provide a valve mechanism such as is indicated at 10, for the purpose of discharging the air admitted between the pistons. The valve mechanism here shown consists of a radially disposed valve 11, operable through the medium of 65 the pivoted lever 12 which is in turn elevated by each individual piston 9. Any air admitted will be compressed against the radially disposed valve member when this is in the inner position, the air being discharged through the opening 13. A further movement of the piston member will then engage the lever 12 and raise the valve member 11, thus permitting a forward movement of the piston. The material discharged into the cylinder will thus drop through the discharge opening 5 into the annular discharge cylinder 6, from where it will be conveyed by the individual piston members and finally discharged as at 14 70 into the lower portion of the compression chamber B. From the receiving chamber or compression chamber, indicated at B, the material may be conveyed through chutes or similar apparatus by gravity to the point of 75 discharge. In some instances, where it is desired to further elevate the material it will only be necessary to connect the chamber through a pipe 15 with a source of pressure supply, such as an air compressor, not 80 here shown. The material may then be conveyed by pressure through pipe 16 to a higher elevation, or to a distant point of discharge, being forced through the line by 85 the medium of the air pressure supplied by 90 the pipe 15.

The apparatus here shown is simple in construction and automatic in operation; the automatic discharging mechanism here shown making it possible to continuously 105 discharge the material elevated by vacuum, thus producing a high efficiency, as practically no air is admitted during the discharge of the material. The application of means for further elevating the material or conveying it to distant points of discharge gives 110 the apparatus a great range of utility, as it

is obvious that the apparatus may be employed for a great variety of purposes.

The materials and finish of the several parts of the mechanism are such as judgment and experience of the manufacturer may dictate.

I wish it understood that various changes in form, proportions and minor details of construction may be resorted to within the scope of the appended claim, and that I do not wish to limit myself to the specific design and construction here shown.

Having thus described my invention, what I claim and desire to secure by Letters Patent is:

In a suction elevator and loader, the combination with a suction chamber having means for conveying material thereto and having a discharge opening formed in its lower end, of an open-ended cylinder connected midway of its ends with the dis-

charge opening, an endless cable passing through said cylinder, means for supporting and driving said cable, a series of piston members secured to the cable adapted to convey the material collected in the suction chamber to a receiving chamber, a slide valve in the upper end of the cylinder to prevent admission of air to the suction chamber and a discharge port formed in the cylinder operable in conjunction with said valve, and a lever pivotally mounted in the cylinder adapted to be actuated by each individual piston member to lift the slide valve.

In testimony whereof I have hereunto set my hand in the presence of two subscribing witnesses.

ROBERT A. SALLEE.
